ADAPTER FOR BASE MOUNTED FILTERS

James W. Wilkinson, Leicester, Mass., assignor
to Fleming Manufacturing Company, a corpora-
tion of Rhode Island

Application January 27, 1938, Serial No. 187,113

11 Claims. (Cl. 210—131)

This invention relates to a filter more particularly of the base mounted type of filter adapted to be used with an internal combustion engine to filter the oil while flowing and the engine is in operation. One of the objects of this invention is the provision of a device which may be positioned on the base and between the base and the casing which is usually mounted directly on the base that certain added functions and advantages or a change in the direction of oil flow through the filter cartridge may be had as desired.

Another object of the invention is to provide for the utilization of casings and cartridges of a different size such for instance as of a larger size than casings designed to be mounted upon the filter base.

Another object of the invention is the provision of a means for offsetting the filter casing from the base so that the casing may be located at various points out of line with and at various angular locations with reference to the center of the base for accommodation in fitting into different locations where difficulty of position is encountered.

Another object of the invention is to convert the differential pressure type of base mounted filter into the clean oil type of filter where a regulated pressure exists upon one side of the filter medium and substantially no pressure exists upon the other side of the filter medium, which conversion eliminates a serious defect in bypasses of the resilient controlled type which has heretofore been existent.

With these and other objects in view, the invention consists of certain novel features of construction, as will be more fully described, and particularly pointed out in the appended claims.

In the accompanying drawings:

Fig. 1 is a sectional view showing the base, the adapter member and the filter casing in assembled relation;

Fig. 2 is a sectional view on substantially line 2—2 of Fig. 1;

Fig. 3 is an elevation of the base at right angles to the position shown in Fig. 1 looking at the mounting plate of the base;

Fig. 4 is a sectional view of the casing and adapter showing the cartridge with perforations indicated in the cylindrical wall thereof;

Fig. 5 is an elevation of the adapter alone;

Fig. 6 is a sectional view on line 6—6 of Fig. 4;

Fig. 7 is a sectional detail on line 7—7 of Fig. 6.

There are in existence today the so-called base mounted filters. These consist of a base which

is usually bolted to the motor, usually the crank case of a motor, and provide for mounting a removable casing on this base which contains a filter cartridge. Means for circulating oil through the cartridge, with a by-pass in the base should the cartridge become clogged, is usually provided. The by-pass, by being connected directly across the inlet and outlet openings with a resilient control, will operate upon a differential of pressures usually set at about four pounds differential. When the circulation of the engine commences there is no pressure upon the discharge side of the base and consequently the by-pass valve opens and by reason of its becoming unseated even though some oil may pass through the cartridge, which is sometimes doubtful, the pressure fluctuates so that the valve is continually vibrating and the spring which operates it becomes fatigued and inoperative.

It is also desirable in many instances to provide a different size of casing to be mounted on the base and at times it also becomes necessary to so shift the base that the filter will miss certain other essential parts of the motor upon which it is mounted which cannot be accomplished by means of the base and casing as a unit always in line in a single operating position, especially if the casing size is increased. Accordingly, I have provided a member which I call an adapter which enables the casing to be offset with relation to the base and which may accommodate a different size of casing by providing different adapters. Also, the adapter provides a separate discharge conduit so that the oil does not pass again through the base and accordingly substantially no pressure in the discharge line is had rather than the necessity of operating by reason of a differential of pressures for the control of the by-pass valve, and thus the by-pass valve spring may be made sufficiently strong so that the valve will not operate upon a mere fluctuation of pressures such as frequently exists in the system; and the following is a more detailed description of the present embodiment of this invention, illustrating the preferred means by which these advantageous results may be accomplished:

With reference to the drawings, 10 designates generally the base, 11 generally the adapter, and 12 generally the casing which is mounted on the adapter. The base 10 is bolted through openings 13 to the crank case of the engine so located that the oil supply conduit emanating from the crank case will match up with the recess 15 provided in the face portion 14 of the base. The oil will

then pass through the conduit 16 and up through the opening 17 of the base and is usually discharged downwardly through central opening 18 through conduit 20 to the conduit 22 and return 23. Recess 15 has opening 19 leading therefrom which connects by means of bore 21 with the opening 23. A by-pass valve 24 operated by spring 25 serves to control conduit 19, 21 connecting the recess from which the entrance conduit 16 leads and the discharge conduit 23 so that should too great a pressure exist on the supply side from that present on the return side the valve 24 will open and permit the oil to by-pass into the discharge 23. This spring control is of such a character that the valve usually opens upon a differential of four pounds pressure which almost always exists at the commencement of flow of oil through the engine. The valve does not close readily due to fluctuations of pressure and because of the fact that once it becomes open it is difficult for it to again close due to the fact that the pressure keeps it open. It is of course understood that the flow may be in the reverse direction through the base from the flow above described, whereby the oil may pass through the cartridge in a reverse direction.

Mounted upon the base is the adapter 11 which consists of a body portion 30 having a rib 31 to enter the recess 29 in the base which was formerly occupied by the cylindrical casing. This adapter is also provided with a bore 32 which is central with respect to the annular rib 31 and accommodates a bolt 33 equipped with an axial bore 34 controlled by a ball valve 35 operated by a spring 36 held within the larger bore 37 and closed by the tubular member 38 having opening 39 therein. Located alongside the bore 32 and its bolt 33, there is a bore 40 providing a valve seat 41 and a ball closure valve 42 which is urged by means of spring 43 onto the seat. A tubular closure member 44 forms an abutment for the spring and also by means of its opening 45 provides access to the bore. The bolt 33 threads into the central bore 28 of the base to fasten the adapter thereto with the rib 31 in the recess 29 forcing the same against a packing 46.

By means of the offset arrangement the adapter may be bound in any one of a variety of angular positions for accommodation of the casing in any one of a variety of angular positions.

Any liquid which has heretofore been delivered to the opening 17 will now be delivered through the opening 45 in the adapter at one side of bolt 33, both of these being located closely adjacent one another, as indicated in Fig. 6. Should the flow have been in through the center at 18 oil would enter through opening 39.

The adapter is provided with a cylindrical wall portion 47 which is provided with a recess 48 at its upper edge for the reception of the wall 50 of the cylindrical casing 12. A central tube 51 is threaded into an opening 52 in the boss 55 of the adapter and held in position by the lock nut 53, there being a washer 54 between the nut and the boss 55. This tube provides for the discharge of the filtrate oil from the casing and connects with a discharge conduit 56 formed as a bore in the adapter and enlarged as at 57 to provide for a threaded nipple or a like connection to a discharge conduit so that the discharge oil does not pass through the base.

A filter cartridge 58 having its cylindrical wall 59 perforated is provided with a central opening having a perforated wall 60 as at 61, which central opening receives the central tube 51 with an

annular space thereabout and with openings 62 leading into it. Cork washers 63 and 64 about the tube 51 seal the annular space at the center of the cartridge so that oil entering either through the passages 39 or 45 must pass through the cartridge filter medium 65 to the annular space to pass through the opening 62 and down to the discharge tube 61 and thence out through conduit 56.

The casing 12 is held in position on the central tube 51 by means of a bolt 66 threaded into the tube 51 which forces this casing down into the recess 48 and against the packing therein and at the same time causes a spring 67 located about the guide collar 68 and also about the tube 51 to force the sealing member 64 down into firm engagement with the cartridge while also forcing the cartridge firmly against the washer 63 supported by nut 53.

In this manner the pressure is entirely relieved on the by-pass existent in the base and a stronger spring 25 may be utilized for holding the valve 24 closed and preventing any chattering of the same and yet allowing action of the by-pass should the pressure build up beyond a certain desired amount indicating a congestion of the filter cartridge. It will thus be apparent that the adapter is bound upon the base independently of the casing and the casing is bound upon the adapter independently of the base being itself bound upon the base and so arranged as to receive oil and pass it from the outside inwardly through the cartridge with the free unrestricted discharge therefrom.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In combination, a filter base having inlet and outlet conduits, a casing to be mounted thereon, an adapter member located between said base and casing, an inlet conduit in said member to receive oil from the base and transmit it to the casing, and a discharge conduit in said member to receive oil from the casing and provide a separate discharge therefor independent of the outlet conduit in the base.

2. In a filter, a filter base having inlet and outlet conduits for connection into a circulating fluid system, a casing above the base and detachably secured in place with respect thereto, an adapter member located between said base and casing, said adapter member comprising a body portion having annular portions projecting outwardly from opposite side faces thereof, one of said annular portions being axially offset relative to the other and serving to locate said adapter with reference to said base, the other of said annular portions to locate said casing with reference to the adapter, an opening in said adapter centrally of each of said annular portions, a hollow coupling extending through one of said openings to form a conduit for inlet of fluid to said casing from said inlet conduit in said base and to secure said adapter to said base, and a central discharge conduit leading from the interior of said casing and communicating with the other of said openings in the adapter member for separate discharge of the filtered fluid independently of the outlet conduit in said base.

3. In a filter, a filter base having inlet and out-

let conduits for connection into a circulating fluid system, a casing above the base and detachably secured in place with respect thereto, an adapter member located between said base and casing, said adapter member comprising a body portion having annular portions projecting outwardly from opposite side faces thereof, one of said annular portions being axially offset relative to the other and serving to locate said adapter with reference to said base, the other of said annular portions to locate said casing with reference to the adapter, an opening in said adapter centrally of each of said annular portions, a hollow coupling extending through one of said openings to form a conduit for inlet of fluid to said casing from said inlet conduit in said base and to secure said adapter to said base, and a central discharge conduit leading from the interior of said casing and communicating with the other of said openings in the adapter member for separate discharge of the filtered fluid independently of the outlet conduit in said base, said adapter member being movable about the axis of said connector to vary the direction and extent of offset of said casing with reference to the normal line of flow of fluid from said base to the adapter.

4. In a filter, a filter base having inlet and outlet conduits for connection into a circulating fluid system, a casing above the base and detachably secured in place with respect thereto, an adapter member located between said base and casing, said adapter member comprising a body portion having annular portions projecting outwardly from opposite side faces thereof, one of said annular portions being axially offset relative to the other and serving to locate said adapter with reference to said base, the other of said annular portions to locate said casing with reference to the adapter, an opening in said adapter centrally of each of said annular portions, a bolt having an axial bore extending through one of said openings to form a conduit for inlet of fluid to said casing from said inlet conduit in said base and to secure said adapter to said base, resilient valve means in said bore controlling fluid communication between said casing and said base, and a central discharge conduit leading from the interior of said casing and communicating with the other of said openings in the adapter member for separate discharge of the filtered fluid independently of the outlet conduit in said base.

5. In combination, a filter base having inlet and outlet conduits for connection into a circulating fluid system, a casing above said base and detachably secured in place with respect thereto, and an adapter member between said base and casing, said adapter member comprising a body portion having annular wall portions projecting outwardly from opposite side faces of said body portion, one of said annular wall portions serving to locate said adapter with reference to said base and the other of said annular portions to locate said casing with reference to the adapter, said wall portions having their axes offset with respect to each other, one of said wall portions also having an inlet opening through said body portion centrally of said wall portion, the other of said wall portions being provided with an outlet opening centrally thereof, a hollow removable tubular coupling engaging in the end of the inlet conduit of said base and extending through said inlet opening of the adapter member to hold said casing and said adapter in liquid-tight engagement and to provide communication between the interior of said casing and said inlet

conduit in said base, a valve in said hollow coupling to prevent return of fluid through said coupling, valve means to prevent return of fluid from the interior of said casing through said adapter into said outlet conduit in said base, and a discharge conduit leading from the interior of said casing and communicating with said outlet opening for discharge of fluid therein.

6. An oil filter comprising a filter base having inlet and outlet conduits for connection into a circulating oil system, the conduits having upwardly extending openings, said base having an upper flange portion with an annular recess at its upper edge of a size to normally fit and seal the end of a casing of one size, an adapter member having an annular rib projecting outwardly from one side face and of a size to fit said recess in the base, said adapter member also having a cylindrical wall portion axially offset from the axis of said rib and projecting outwardly from the opposite side face of said adapter member with an annular recess in the upper edge of said wall portion of a size to fit a casing of a different size, an inlet opening through said adapter and central of said annular rib, a bolt having an axial bore to form an inlet of fluid to said casing from said inlet conduit in said base, said bolt extending through the inlet opening in said annular member and securing the same to said base and in communication with the inlet conduit thereof, an outlet opening in said adapter located centrally of said cylindrical wall portion thereof, a casing above said base and detachably secured in place in said upper recess in said wall portion of said adapter member, said casing being open at the bottom for inlet of oil from said bolt, filtering material within said casing, and a central discharge conduit extending upwardly through said filtering material and communicating at its lower end with said outlet opening in said adapter to provide a separate discharge for the filtered oil independently of the outlet conduit in said base.

7. In combination, a filter base having an enlarged annular portion, a cylindrical casing, and an adapter member located between said base and said casing for mounting the latter on said base, said adapter having an enlarged annular portion of a size to fit said enlarged annular portion of said base and locate and laterally retain said adapter thereon, and another enlarged annular portion of a size to receive and laterally retain said casing on said adapter and to axially offset said casing from said base in the assembled position of the parts.

8. In combination, a filter base having an enlarged annular portion, a cylindrical casing, and an adapter member located between said base and said casing for mounting the latter on said base, said adapter having an enlarged annular portion of a size to fit said enlarged annular portion of said base and locate and laterally retain said adapter thereon, and another enlarged annular portion of a size to receive and laterally retain said casing on said adapter and to axially offset said casing from said base in the assembled position of the parts, said adapter member being movable on said base about said enlarged annular portions of said base and the adapter into different adjusted positions to vary the extent and direction of offset of the casing with respect to said base.

9. In combination, a filter base having an annular portion of a size to locate and laterally retain a cylindrical casing of one size, a casing

of a size different than would normally fit on said annular portion of the base, and an adapter member located between said base and casing, said adapter having an annular part of a size to locate and laterally retain the adapter on the annular portion of said base, and another annular part of a size to locate and laterally retain the casing on the first annular part of the adapter, said annular locating parts of the adapter being so disposed relative to each other that the casing will be axially offset from said base when said casing and adapter member are mounted in assembled position on said base.

10. In combination, a filter base having an annular recess of a size to receive and laterally retain a cylindrical casing of one size, a casing of a size different than would normally fit on said annular portion of the base, and an adapter member located between said base and casing, said adapter having an annular projection on one side of a size to fit into said annular casing-receiving recess on the base, an annular recess on the opposite side of said adapter centrally offset from the center of said annular projection and of a size to receive and laterally retain said casing 25

on the adapter and to axially offset said casing from said base when said casing and adapter member are mounted in assembled position on said base.

5. 11. In combination, a filter base having an annular recess of a size to receive and laterally retain the open end of a cylindrical casing of one size, a cylindrical casing having an open end of a size different than would normally fit inside of said recess of the base, and an adapter member carried by said base and located between the base and said casing for supporting the latter, said adapter having on one side an enlarged annular projection of a size to fit into and be laterally retained by the annular recess in said filter base, and having on the other side an enlarged annular recess of a size to receive and laterally retain the open end of said casing, means for detachably securing said casing to said adapter, and means independent of said casing-securing means for detachably securing said adapter to said base, said adapter securing means having no attachment to said casing.
